(57) **CLAIM**

The ornamental design for a pin striped thin film solar module for cluster lamp, as shown and described.

DESCRIPTION

FIG. 1 is a perspective view of the pin striped thin film solar module for cluster lamp showing the new design;

FIG. 2 is a front elevational view thereof;

FIG. 3 is a top plan view thereof;

FIG. 4 is a bottom plan view thereof;

FIG. 5 is a side elevational view thereof; and,

FIG. 6 is a bottom perspective view thereof.
